DOFFING ROLL FOR CARDING MACHINES

Original Filed Aug. 4, 1925 2 Sheets-Sheet 2

UNITED STATES PATENT OFFICE.

ERNEST L. CADY, OF HARTFORD, CONNECTICUT, ASSIGNOR TO THE E. L. CADY ENGINEERING COMPANY, OF HARTFORD, CONNECTICUT, A CORPORATION OF CONNECTICUT.

DOFFING ROLL FOR CARDING MACHINES.

Application filed August 4, 1925, Serial No. 48,071. Renewed February 1, 1929.

This invention relates to carding machines and particularly to an improved form of doffing roll adapted to facilitate carding operations upon materials having extremely 5 short fibres.

An object of the present invention is to provide a doffer roll of the ring type having card clothing thereon and also having members interposed between the needles of the 10 card clothing adapted to aid in removing the fibres being carded from the needles of the doffer on to the condenser bands.

Another object of importance is to provide means for moving the members interposed between the needles of the card clothing longitudinally of the needles in timed relation to the rotation of the doffing roll so that the fibres may be loaded upon the needles at one point and forced from said needles at 20 another point.

One feature of importance which enables me to accomplish the above named objects is that independent members are interposed between the card clothing needles extending 25 across the width of the needles on each ring. Between the rings of needles are bands or rings for retaining the members in operative position and means for actuating them during rotation of the doffing roll.

Another feature of importance is that eccentric means relative to the rings of card clothing on the doffing roll and having means interposed between itself and the bands are provided to actuate the members during the 35 rotation of the doffer roll.

In doffer rolls as heretofore employed, spaced rings of card clothing are mounted on a small cylinder or roll which rotates adjacent a large cylinder on which fibres are laid. The 40 card clothing on the doffing roll during rotation of the roll and large cylinder strips the fibres from the card clothing on the large cylinder. The rings of card clothing on the doffing roll then give up the fibres being carded to condensers usually in the form of wide 45 belts between which the fibres are worked while the belts are vibrated laterally. The above method of doffing fibres at the end of the carding operation is satisfactory for fibres of long or fairly long staple. In the case

of short staple material, such as asbestos, wood pulp or other materials, fibres of longer staple are required to be added by being mixed with the material being carded for satisfactory operation. In the case of asbestos this is a serious disadvantage as no other material having fibers of long staple exists having similar fire-resisting properties. It is particularly desirable, therefore, in the case of carding asbestos to provide means 55 whereby the carding operation can be carried out with pure asbestos, that is, without the addition of cotton, hemp or other fibres of longer staple.

In operations upon materials of short 60 staple the difficulty has not been in the carding process itself but rather in withdrawing the fibres from the doffer rolls and placing them upon the condenser rolls in continuous strips. Applicant's invention therefore 65 resides in the doffing roll of a carding machine and more especially in a doffing roll provided with members movable relative to the needles of the card clothing during rotation and adapted to aid the fibres in being stripped 70 from the needles of the doffing roll and conveyed to the condenser. Also, this is accomplished without subjecting the fibres, as they 75 are being stripped from the doffer needles, to tension sufficient to separate them.

At all times while the fibres are on the doffing roll they are being pushed or forced outwardly along the needles of the card clothing by the outward movement of end surfaces of the interposed members. These end 85 surfaces are such that the fibres can rest upon them and their removal from the needles is without subjecting the fibres to any tendency to separate.

With the above and other objects in view 90 my invention consists in the features of construction and operation set forth in the following specification and illustrated in the accompanying drawings.

In the accompanying drawings annexed 95 hereto and forming a part of this specification, I have shown my invention embodied in an asbestos-fibre carding machine but it will be understood that the invention can be otherwise embodied and that the drawings 100

are not to be construed as defining or limiting the scope of the invention, the claims appended to this specification being relied upon for that purpose.

5. In the annexed drawings:

Figure 1 is a fragmentary end elevation of a carding machine provided with the present form of doffing roll shown partly in section.

10. Fig. 2 is a longitudinal view of the doffing roll shown partly in section.

Fig. 3 is an enlarged view of portions of the carding machine cylinder and the doffing roll, showing the position of the members interposed between the needles when the fibres 15 are being laid upon the doffing roll.

20. Fig. 4 is a view on the same scale as Fig. 3 showing the doffing roll and condenser, the interposed members being positioned after stripping the fibres from the doffing roll 25 needles so that they may move on to the condenser bands.

Fig. 5 is a longitudinal sectional view of the doffing roll taken on line 5—5 of Fig. 1.

25. Fig. 6 is a similar sectional view taken on line 6—6 of Fig. 1; and

Fig. 7 is a perspective view of the interposed members and their retaining and actuating member, the doffing roll and its card clothing being removed.

30. In the above-mentioned drawings, I have shown but one embodiment of the invention which is now deemed preferable, but it is to be understood that changes and modifications may be made within the scope of the appended claims without departing from the spirit of the invention.

Briefly, and in its broadest aspect, my invention comprises the following principal parts, first a doffing cylinder having applied thereto spaced rings of card clothing, second, members disposed between the needles of said clothing and lying substantially parallel to said rows of needles, third, lateral extensions on the sides of said members adapted to be engaged by rings or bands to retain them in position, fourth, a cylinder disposed within and eccentrically relative to said doffing cylinder and, fifth, means extending through said doffing cylinder and engaging said eccentric cylinder and said rings so that the members between the needles of the card clothing are movable substantially radially of the doffing cylinder during rotation of the doffing cylinder.

55. Referring more in particular to the figures of the drawings I provide a doffing cylinder 10 for a carding machine mounted, as usually found in these machines, adjacent the central large cylinder 11 of the machine. The doffing cylinder or roll 10 comprises a metal tube or cylinder 12 and oppositely disposed heads 13 at its ends, one of which is shown in Figs. 1 and 2. These heads 13 may be provided with journal portions 14 adapted to be

70. rotatable within bearings provided in standards 15. Preferably and as shown in the figures, the heads 13 have a central opening through their journal portions for a purpose which will be defined hereinafter.

Surrounding the metal tube 12 are secured, as by screws 12^a, wooden strips 16 to which the card clothing 17 is attached. This card clothing 17, as usual in ring doffing types of carding machines, is in the form of rings 75 or circular strips extending entirely around the cylinder but suitably spaced apart. Adjacent the doffing cylinder 10 are the condenser rolls 18 over which extend wide leather bands 19 between which the fibres pass 80 after leaving the doffing cylinder 10. These rolls 18 are adapted to be rotated and simultaneously moved axially in the usual manner.

85. Disposed between the needles so that they always extend partially within the space between the needles are spaced members 20 formed of sheet metal and of a height substantially less than that of the needles. These members 20 which are of plate-like

90. form are provided with lateral extensions 21 on opposite sides. As shown, the body portions of the members are approximately as wide as the rings 17 of card clothing and the lateral projections 21 extend into the spaces between the strips of card clothing 17. In 95.

95. Inserted within these spaces are metal rings 22 upon which the projections 21 are adapted to rest. Surrounding the rings 22 and bearing upon the outer surfaces of the projections 21 are metal rings 23. It will be seen 100 from this construction that the interposed members 20 are held in position between the needles of the card clothing 17 by means of the inner or outer rings or bands 22 and 23. In the drawings a member 20 is shown as being disposed obliquely between each row of 105. needles. It will be understood however that members 20 may be disposed between alternate, every third, or any other number of rows of needles if desired and if the fibres do 110 not require additional support.

110. Within the metal cylinder 12 is another cylinder 25 also preferably of metal and supported upon heads 26 at opposite ends, one only being shown in Fig. 2. The heads 26 115 are carried upon a shaft 27 rotatably mounted in any suitable bearings (not shown). The position of this cylinder 25 relative to cylinder 12 is clearly indicated in Fig. 1 as being eccentric thereto. The axis of cylinder 25 is directly away from the main cylinder 11 of the machine and toward the condenser rolls 18. The axes of the cylinders 12 and 25 are therefore substantially in a horizontal plane and parallel to each other.

120. Disposed loosely in suitable apertures extending through the cylinder 12 and through the wooden strips 16 so that they may move freely therethrough are spacers or pins 30 their inner ends adapted to rest upon the 130

cylinder 25 and their outer ends adapted to engage the inner surface of the rings or bands 22. Rotation of the cylinders 12 and 25 will therefore cause the pins 30 to move inward 5 and outward and move the bands 22 and the parts supported thereon relative to the cylinder 12 and card clothing 17 due to the eccentricity of these cylinders. The members 20 will be withdrawn inwardly at that portion 10 of the doffing cylinder 12 toward the main cylinder 11 and will be extended outwardly beyond the ends of the needles of the card clothing 17 at the opposite side and toward the condenser 18. Preferably the cylinders 12 and 25 are simultaneously rotated so that the pins 30 do not frictionally engage and slide over the surfaces of the cylinder 25 and the rings 22.

The members 20 are of greater length than 20 the distance they are moved radially of the cylinder 12 or along the needles of clothing 17. Portions of these members will therefore always be within the space directly between the needles.

25 Positioned below the cylinders 12 and 25 is a plain cylindrical roll 32 adapted to lightly contact with or just clear the card clothing 17 on cylinder 12. At the point of the periphery of cylinder 12 at which the roll 32 is placed the members 20 are moving outwardly relative to the needles of the card clothing and their outer edges are substantially even with the outer free ends of the needles. The fibres on the needles will therefore be forced outward along the needles by movement of these members 20 and will be compressed and compacted by the roller 32 prior to their being advanced to the condenser strips or bands 19.

40 Beyond the roller 32 the members 20 continue to move outward and, when the condenser bands 19 are reached, the closely compacted fibres are entirely free from the needles of the clothing 17. They are therefore 45 supported upon the adjacent end surfaces of the members 20 ready to move directly onto the condenser bands 19 without any tendency of the card clothing needles separating them or subjecting them to tension.

50 The operation of the above described construction is substantially as follows: The fibres being carded are carried by the main cylinder 11, after having been operated on by the usual strippers and worker rolls with 55 which the carding machine is provided, to the card clothing 17 on the doffing roll 12. Usually two or more of these doffing rolls or cylinders 12 are provided for each main cylinder 11, having spaced rings or bands of card clothing 17. The directions of rotation of the main cylinder and the doffing roll 10 are as indicated by arrows in Fig. 1. The fibres on the cylinder 11 are carried over from the card clothing on the main cylinder 11 to that 60 on the doffing roll 12. At the point at which

these fibres are transferred to the doffing roll 12 the members 20 are retracted so that the needles of the card clothing 17 on the doffing roll 10 are loaded with fibres in the usual manner. As the doffing roll 10 rotates in the 70 manner shown, the members 20 move outwardly due to the eccentric position of the cylinder 25 until, when the condenser strips 19 are reached the members 20 have moved to positions so that their outer ends extend 75 slightly beyond the outer free ends of the card clothing 17. The fibres therefor will be positioned upon the adjacent outer end surfaces of the members and may be laid directly upon the condenser bands 19 without any tension or pulling of the fibres from the needles. Preferably the members 20 are of material thickness and fill up the major portion of the space on the roll 12 between the needles of the card clothing 17. The fibres deposited on 80 the needles of the doffing roll clothing 17 are therefore supported by and rest upon the outer edges of these members. During the movement outward of the members 20, the roller 32 engages the fibres while resting upon the end surfaces of these members so that the fibres are compressed and made to adhere more closely together. The thin band of short fibres may therefore be carded and advanced to the condenser bands without any 95 tendency to their becoming separated.

I claim:

1. A doffing roll for carding machines comprising in combination, a cylinder, card clothing thereon, plate-like members interposed between and parallel to the needles of said clothing for supporting and stripping the fibres being carded from said needles, and means to move said members a portion of their width along said needles during the rotation of said cylinder.

2. A doffing roll for carding machines comprising in combination, a cylinder, card clothing thereon, spaced plate-like members interposed between and parallel to the needles of said clothing for supporting and stripping the fibres being carded from said needles, a cylinder eccentric to said first cylinder, and means on said last mentioned cylinder for moving said spaced members a portion of their width along said needles during the rotation of said first cylinder.

3. A doffing roll for carding machines comprising in combination, a cylinder, spaced annular strips of card clothing thereon, members interposed between the needles of said clothing for supporting and stripping the fibres being carded from said needles, means to move said members along said needles, and means between said annular strips of card clothing to retain said members in operative position.

4. A doffing roll for carding machines comprising in combination, a cylinder, card

clothing thereon, plate-like members interposed between the needles of said clothing for supporting and stripping the fibres being carded from said needles, the thickness of 5 said members being adapted to substantially fill the space between said needles, and means to move said members during the rotation of the cylinder whereby the outer ends of said members move from within to positions 10 beyond the free ends of said needles, other portions of said members remaining between the needles.

5. A doffing roll for carding machines comprising in combination, a cylinder, card clothing thereon, members interposed between the needles of said clothing for supporting and stripping the fibres being carded from said needles, projections on said members, bands engaging the inner and outer 20 surfaces of said projections, and means engaging said bands to move said members along said needles during the rotation of said cylinder.

6. A doffing roll for carding machines comprising in combination, a cylinder, card clothing thereon, members interposed between the needles of said clothing for supporting and stripping the fibres being carded from said needles, means to move said members a portion 25 of their width along said needles from between to partially beyond the needles during the rotation of said cylinder, and a roll adjacent to the clothing of said cylinder, said roll being positioned adjacent the cylinder substantially at that point where said members project beyond the free ends of said 30 needles.

7. A carding machine comprising in combination, a base, a main cylinder rotatable 40 thereon, a doffer roll adjacent said main cylinder and rotatable on said base, card clothing on said cylinder and roll, members interposed between and parallel to the needles of said card clothing, positive means to move 45 said members relative to said needles, said members being within said needles when closely adjacent said cylinder and movable to extend partially beyond the outer ends of 50 said needles as said needles are rotated away from said main cylinder.

8. A doffing roll for carding machines comprising in combination, a cylinder, card clothing thereon, members interposed between the 55 needles of said clothing for supporting and stripping the fibres being carded from said needles, means to move said members along said needles during the rotation of said cylinder to extend partially beyond said needles 60 in one position of said doffing roll, and means adjacent the doffing roll and substantially in contact with the outer ends of the needles of the card clothing and positioned substantially at that point where said members project beyond the free ends of said needles on 65

their movement outward to compress and solidify the fibres being carded.

In testimony whereof, I hereto affix my signature.
